Primary Examiner — T. Chase Nelson
Assistant Examiner — Ania Aman(74) *Attorney, Agent, or Firm* — Michael Best & Friedrich LLP(57) **CLAIM**

I claim the ornamental design for an engine cam cover, as shown and described.

DESCRIPTION

FIG. 1 is a perspective view of an engine cam cover;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines shown in the drawings are for the purpose of illustrating portions of the article that form no part of the claimed design.

1 Claim, 6 Drawing Sheets(56)
